ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

THREAD-PARTING MECHANISM FOR LOOMS.

No. 922,511.

Specification of Letters Patent.

Patented May 25, 1909.

Application filed February 27, 1909. Serial No. 480,322.

To all whom it may concern:

Be it known that I, ALONZO E. RHOADES, a citizen of the United States, and resident of Hopedale, county of Worcester, State of Massachusetts, have invented an Improvement in Thread - Parting Mechanism for Looms, of which the following description, in connection with the accompanying drawing, is a specification, like characters on the drawing representing like parts.

My present invention relates to automatic looms wherein the working shuttle is provided with a fresh supply of filling prior to complete exhaustion of the previous supply, and such invention has more particular reference to the mechanism for parting near the shuttle the old filling-end which extends from the cloth to the shuttle containing the filling-supply or bobbin about to be abandoned. In such mechanism the old filling-end has heretofore been positively clamped and parted near the shuttle and the clamped end has been drawn forward to bring it into the field of action of a temple thread-cutter, to be severed close to the cloth, and in order to prevent breakage of the clamped filling-end by the forward movement of the clamping and parting instrumentality to normal position such instrumentality has been moved bodily in a diagonal path toward the edge of the cloth. Examples of such mechanisms are found in United States Patents No. 683,423, September 24, 1901 Draper, and No. 897,404 granted to me September 1, 1908.

This present invention has for its object the production of novel means for effecting and controlling the movement of the clamping and parting instrumentality away from and toward the cloth, to the end that an easier movement of such instrumentality is secured, with less wear upon the parts and requiring a diminished expenditure of power to effect the desired results.

In the subjoined specification I have fully described the construction and operation of my invention, with especial reference to the novel features thereof, and have particularly pointed out the same in the following claims.

Figure 1 is a transverse section, on line 1—1, Fig. 2, of a sufficient portion of a loom with my present invention applied thereto, the various parts of the mechanism being shown in normal, inoperative position; Fig. 2 is a top plan view of the greater portion of

the mechanism illustrated in Fig. 1, and in 55 the same position; Fig. 3 is a view similar to Fig. 2, with the lay farther forward and with the thread parting and clamping instrumentality in operative position to clamp and part the old filling-end and just prior to the 60 return movement of said instrumentality to normal position; Fig. 4 is a front elevation of the controlling cam for the shuttle-feeler.

Referring to the drawings, the lay A^3 having a shuttle-box B at the replenishing side of the loom, the rocking transerrer f' , see dotted lines Fig. 1, to remove the filling-carriers or bobbins b^x from the filling-feeder or hopper F to the shuttle, and the controlling rock-shaft d' , may be and are of well 70 known construction, the lay having a bunter C^2 to coöperate with the notched dog m^x when filling is to be replenished in the working shuttle S.

In the practical embodiment of my present invention as herein disclosed a bracket 1 fixedly attached to the loom-side sustains a horizontal, inwardly extended stud 2 on which is mounted the hub 3 of a short arm 4 having at its forward end a yoke-shaped enlargement 5 provided with aligned and separated bearings 6, 7, Fig. 1, and a lateral pin 3^x extends from the enlargement 5, the bearings being located above and below the fulcrum stud 2, respectively, as shown in Fig. 1. 80 Said arm and yoke constitute a carrier for the shuttle-feeler, the carrier being adapted to swing about the stud 2 as a fulcrum, the rock-shaft d' being operatively connected with the carrier by or through arm d^{12} fast 90 on the rock-shaft and by the jaw d^{14} pivoted on the arm d^{12} and acted upon by a spring S^x , the parts d^{12} and d^{14} conjointly coöperating with the pin 3^x of the carrier, to control its swinging movement substantially as in 95 Patent No. 677,096 granted to Northrop June 25, 1901.

When the rock-shaft d' is turned in the direction of arrow 100 the carrier is swung upward and rearward upon stud 2 to operatively position the shuttle-feeler, to be described, and by means of a cam-slotted arm Y^x , bolted at 8 to the yoke of the carrier, the notched dog m^x is permitted to swing into the path of the bunter C^2 , in the usual 105 manner when replenishment of filling is called for.

Herein the shuttle-feeler 9 is shown as the

enlarged and flattened upper and rearwardly-extended portion of an inclined and upturned shank 10 having a cylindrical portion 11 below a shouldered part 12 seated on the top of the bearing 6 on the carrier, the portion 11 constituting an elongated journal, which is pivotally extended through the bearings 6 and 7. A washer 13 and cotter-pin 14, Fig. 1, below the bearing 7, prevent accidental withdrawal of the journal from its bearings. This construction provides a strong and unyielding pivotal connection between the shuttle-feeler and the swinging carrier, having practically the function of a long sleeve or hub yet of relatively light weight by reason of the bifurcated structure of the yoke 5 of the carrier, so that while the shuttle-feeler can be freely swung laterally with relation to the carrier it is firmly sustained without possibility of twisting, and is securely connected with the carrier.

The fulcrum 2 for the carrier and the journal 11 of the shuttle-feeler are at right angles to each other as herein shown so that the fore and aft movement of the feeler is with the carrier on the stud 2, and its lateral movement relatively to the carrier is about the journal 11.

A forwardly extended arm or follower 15 on the shank of the feeler adjacent the journal travels in a cam-slot 16 formed in an upright ear 17 shown as a part of the bracket 1 and constituting a controller for the shuttle-feeler in its movements relative to the swinging carrier, the controller being curved longitudinally about the stud 2 as a center, and viewing Fig. 4 the cam-slot 16 of said controller is straight and upright at its upper end, at $16^\times$, and slightly curved and extended diagonally toward the loom-side below said straight portion. By this structure a very easy movement is provided for the shuttle-feeler when moved laterally relatively to the carrier when the latter is swung on its fulcrum 2, but the structure is exceedingly simple and easily made. While the controller thus easily governs the feeler the control is very exact, and there is no opportunity for twisting or lost motion tending to improperly divert the feeler from its proper path, the structure being very strong and durable and providing large bearing surfaces wherever such surfaces are required. The diagonal part of the groove in the controller serves to swing the shuttle-feeler laterally about the journal 11 toward the mouth of the shuttle-box on the backward swing of the feeler-carrier, and away from the mouth of the box on the forward swing, while the straight part $16^\times$ of the groove maintains the feeler in a straight path as it crosses the mouth of the box on its final movement to feeling position.

From the foregoing it will be manifest that when filling-replenishment is called for the

carrier is swung rearward to the position shown in Fig. 3, carrying the feeler with it, but the follower 15 by coöperation with the controller will be moved on its journal or fulcrum 11 into operative position across the mouth of the shuttle-box B, as in Fig. 3. The feeler is thus moved away from the edge of the cloth as it is moved to operative position and the reverse action is effected upon return movement of the feeler to normal position, shown in Figs. 1 and 2.

The tip of the feeler 9 is notched at $9^\times$ to receive the old filling-end when the feeler is moved into operative position, and suitable means to clamp and part such filling-end is mounted upon the feeler, such for instance as shown in Patent No. 834,269 granted October 30, 1906 to Cunniff. A fixed blade 16' is secured to the feeler adjacent the lower edge of the notch, and the movable blade 17' is fulcrumed on stud 18, to coöperate with the fixed blade and part the thread while also coöperating with the plate 19 constituting the fixed member of the thread clamp, as in the Cunniff patent. The movable member 17' of both clamp and thread-parter has a heel 20 which is struck by the advancing lay, to first clamp the filling-end t , Figs. 2 and 3, and then to part it at the side nearest the shuttle, the clamp remaining closed upon the thread when the feeler returns to normal, inoperative position. Inasmuch as the feeler is moved toward the edge of the cloth at such time the clamped length of the parted thread is slackened and strain removed therefrom as it is moved into position to be engaged by the usual thread-cutter $t^\times$ on the temple T, Figs. 2 and 3, obviating danger of thread breakage. The clamping and parting instrumentality is closed when the feeler is in normal position and hence must be set or opened before operative positioning of the shuttle-feeler, to coöperate with the old filling-end, and herein I have shown the setting device mounted upon an upturned arm 21 fulcrumed at 22 on a part of the bracket 1 and having a depending stop lug 23 held against the bracket by a spring 24, Fig. 1.

A spring controlled cam rib 25 is pivoted at 26 on the rearwardly extended end 27 of the arm 21, and as the feeler moves rearward to operative position a lateral pin 28 on the heel of the movable member 17' of the clamp and parter passes under the cam rib, the latter then acting to swing the member 17' into open position. After the clamp has been closed the pin 28 wipes over the top of the cam rib 25 and depresses it against its spring 29, see dotted lines Fig. 1, as the feeler returns to normal position, so that the cam rib 25 has no effect upon the clamp, the general structure and operation of the setting device being substantially as in the Draper patent No. 683,423 hereinbefore mentioned.

The upper edge of the extension 27 of the

arm 21 is convexed or rounded, as shown best in Figs. 2 and 3, and substantially horizontal along the rearmost part, as shown in Fig. 1, to sustain the filling-end after it has 5 been severed close to the edge of the cloth by the temple thread-cutter, thereby preventing the piece of thread from falling onto and possibly clogging the clamping and parting instrumentality.

10 Other means for clamping and parting the filling-end may be used instead of that herein illustrated.

As shown in Fig. 1 a lug 30 on the yoke 5 is adapted to engage the part of the bracket 15 1 below the pivotal support of the arm 22 when the shuttle-feeler and parts mounted thereon are moved to operative position, to limit such movement and provide a fixed stopping point therefor.

20 Having fully described my invention, what I claim as new and desire to secure by Letters Patent is:—

1. In an automatic filling - replenishing loom, a swinging carrier having a yoke-like 25 enlargement provided with separated and alined upper and lower bearings, a shuttle-feeler having an elongated journal pivotally mounted in said bearings, a forwardly extended follower rigidly connected with the 30 feeler adjacent the journal, a controller co-operating with the follower to rock the feeler laterally relatively to the carrier when the latter is swung to effect bodily movement of the feeler, and means carried by the latter to 35 clamp and part the thread of the filling-supply to be abandoned.

2. In an automatic filling - replenishing loom, a swinging carrier, a fixed, horizontal support therefor, alined upper and lower 40 bearings on the carrier, separated from each other and at right angles to the carrier support, a shuttle-feeler having a depending journal mounted in said bearings, whereby the feeler is movable with the carrier and also 45 laterally relatively thereto, means on the feeler to clamp and part the thread of the filling-supply to be abandoned, and means to control the lateral movement of the feeler and cause it to move toward the edge of the 50 cloth as the carrier returns to normal position after filling replenishment.

3. In an automatic filling - replenishing loom, a swinging carrier, a fixed, horizontal support therefor, alined and separated bearings on the carrier above and below the support thereof and at right angles thereto, a shuttle-feeler journaled in said bearings and movable laterally relatively to the carrier, a 55 thread clamping and parting instrumentality 60 on the feeler, and means to move the feeler laterally in one direction when the carrier is swung into operative position and to reverse

the lateral movement of said feeler when the carrier returns to normal position.

4. In an automatic filling - replenishing 65 loom, a swinging carrier, a fixed, horizontal support therefor, alined and separated bearings on the carrier above and below the support thereof, a shuttle-feeler journaled in said bearings and movable with the carrier and 70 also laterally relatively thereto, a thread clamping and parting instrumentality on the feeler, and means to control the lateral movement of the feeler when the carrier is swung about its support, said means comprising an 75 upright, fixed ear having a cam slot, and a follower rigidly connected with the feeler and caused to traverse the slot by swinging movement of the carrier.

5. In an automatic filling - replenishing 80 loom, a swinging carrier having a fixed fulcrum, separated and alined bearings mounted on the carrier, a shuttle-feeler having an elongated journal pivotally mounted in the bearings, a thread clamping and parting instrumentality mounted on the feeler, an upright, fixed controller having a cam slot, and a follower rigidly connected with the feeler adjacent the journal and caused to traverse the cam slot by swinging movement of the 90 carrier, to effect lateral movement of the feeler relatively to the carrier.

6. In an automatic filling - replenishing loom, a swinging carrier having a fixed fulcrum, separated and alined bearings, mounted 95 on the carrier, a shuttle-feeler having an elongated journal pivotally mounted in the bearings, a shoulder at the upper end of the journal to rest upon the top of the upper bearing, a thread clamping and parting instrumentality mounted on the feeler, and means to control lateral movement of the feeler about its journal as a center when the carrier is swung about its fulcrum. 100

7. In an automatic filling - replenishing 105 loom, a swinging carrier having a fixed fulcrum, alined bearings mounted on the carrier above and below its fulcrum, a shuttle-feeler having a depending shank pivotally mounted in said bearings to rock laterally relatively to 110 the carrier, a thread clamping and parting instrumentality mounted on the feeler, and follower extended from the feeler shank adjacent the bearings, and a fixed cam-like controller co-operating with the follower to 115 govern the lateral movement of the feeler when the carrier is swung upon its fulcrum.

In testimony whereof, I have signed my name to this specification, in the presence of two subscribing witnesses.

ALONZO E. RHOADES.
